Primary Examiner—Martie K. Holtje*Attorney, Agent, or Firm*—Renner, Otto, Boisselie & Sklar, PLLC[57] CLAIM

The ornamental design for a golf ball and business card holder, as shown and described.

DESCRIPTION

FIG. 1 is a perspective view of one form of a golf ball and business card holder in accordance with this invention as seen from the left front;

FIG. 2 is a side elevation view of FIG. 1 as viewed from the right side, the left side being substantially a mirror image;

FIG. 3 is a top plan view of FIG. 1;

FIG. 4 is a bottom plan view of FIG. 1;

FIG. 5 is a perspective view of another form of a golf ball and business card holder in accordance with this invention as viewed from the left front;

FIG. 6 is a side elevation view of FIG. 5 as viewed from the right side;

FIG. 7 is a side elevation view of FIG. 5 as viewed from the left side;

FIG. 8 is a front elevation view of FIG. 5;

FIG. 9 is a rear elevation view of FIG. 5;

FIG. 10 is a top plan view of FIG. 5; and,

FIG. 11 is a bottom plan view of FIG. 5.

The broken line showing of a golf ball and business cards in FIGS. 1 and 5 is for illustrative purposes only and forms no part of the claimed design.
